UNITED STATES PATENT OFFICE.

CHARLES SUTTER, OF SURESNES, FRANCE, ASSIGNOR TO SOCIÉTÉ ANONYME DES
ANCIENS ÉTABLISSEMENTS HOTCHKISS ET COMPAGNIE, OF ST. DENIS, FRANCE.

FIRING MECHANISM FOR AUTOMATIC FIREARMS.

Application filed July 21, 1924. Serial No. 727,313.

To all whom it may concern:

Be it known that I, CHARLES SUTTER, citizen of the Republic of France, residing at 42 Rue Emile Zola, Suresnes, Seine, France, have invented new and useful Improvements in Firing Mechanisms for Automatic Firearms, of which the following is a specification.

The present invention relates to a firing mechanism for automatic fire-arms. This 10 firing mechanism renders it possible, by suitably placing a lateral lever acting upon an axis which passes through the casing, to effect either continuous or machine-gun 15 firing, or single-shot firing in which latter case it is necessary after firing a shot, to release the trigger and to actuate it again, or again to assume the safety position, which, while not preventing cocking the 20 gun, does not permit of firing a shot whatever may be the action exerted upon the trigger.

The mechanism according to the invention, is essentially characterized by the combination 25 of a trigger, a sear, a lever pivoted at one extremity on the trigger and acting with its other extremity upon the sear, and of a single spring connecting the lever and the sear and ensuring the return 30 of the sear, the trigger and the sear-lever.

The invention also comprises a safety device which can assume three positions by 35 rotating upon itself, and in which it presents, opposite to an inclined plane of the sear-lever, either a flattened surface which has no action upon the plane, or a circular portion which acts upon the inclined plane in such a manner that the lever is disengaged from the sear, at the end of its rearward stroke, or, finally, it presents an eccentric projection which releases the lever from the sear so as to prevent any action 40 of this lever upon the sear, if the trigger is pulled. The invention is shown diagrammatically and by way of example in the accompanying drawings in which:

Figs. 1 and 1^a are longitudinal sectional views of an automatic gas-operated gun, provided with the firing mechanism according to the invention.

Fig. 2 shows the firing mechanism in the position corresponding to continuous fire, the trigger being held by the finger.

Fig. 3 shows the mechanism in the position for single shot firing, the trigger being held by the finger.

Fig. 4 shows the mechanism in the safety position.

Fig. 5 is a plan view of the whole of the firing mechanism.

The firing mechanism is mounted in a casing 1 and is located beneath the weapon, under which it is held by the pin 2 and by a movable pin 3 (Fig. 5).

The parts of the mechanism comprise: the 65 sear 4, upon which will be noticed the head carrying the engaging hook 5, tail-piece 6 and its eye for the reception of the spring 7; the arm 8 slotted for the passage of the 70 sear-lever 9 and the shoulder 10; the sear 75 is pivoted upon the casing around the axis 11.

The sear-lever 9 has a hole 12 into which the spring 7 can be hooked, a head 13 pivoted upon the trigger about an axis 16, an 80 inclined plane 14 co-operating with the safety lever and a hook 15 acting upon the arm 8 of the sear.

The trigger 17 is slotted in the centre at its upper end so as to receive the head 13 85 of the lever 9, and carries a shaft 16 fixed thereto, about which the lever can pivot.

The safety device consists of an axis 18 which can be operated by an external flexible lever 19; a pin fixes this lever in three 90 different positions; the axis 18 has a flattened portion 20 and a projection 21.

It will be noticed that a single spring 7 acts upon the sear 4, upon the sear-lever 9 and upon the trigger 17; on the other hand, 95 the sear-lever 9 engaging the pivot 16 of the trigger 17, is held thereon when assembling and dis-assembling the mechanism by the tube 22 which serves as an axis for the trigger; finally, the front portion of the 95 sear-lever 9 carrying the hook 15 is positioned by the slot formed in the bottom of the arm 8 of the sear 4.

The method of operation is as follows: 100 The mechanism is shown at rest in Fig. 9. The head of the sear projects into the receiver; if the weapon is cocked by hand, the piston, or any other movable member in any other type of weapon, meets the inclined plane of the head 5 of the sear; this 105 latter moves down, thereby tensioning the

spring 7 and moves up again as soon as it meets its recess in the piston or other movable member. If the cocking movement is stopped, the piston advances under the action of its returning spring, which was tensioned during the recoil, and engages the sear 4.

The safety lever 18, 19 having been placed for continuous fire (Figs. 1 and 2), if the trigger 17 is pulled, it takes with it the sear-lever 9, by means of its axis 16, and the sear-lever causes the sear 4 to oscillate by means of its hook 15; the head of the sear 5 gives way and the piston is released; the shaft 18 presents its flattened portion 20 to the inclined plane 14 of the sear-lever 9; this latter cannot release itself from the arm 8 of the tail of the sear, the head 5 remains in its lowermost position as long as pressure is exerted upon the trigger 17 and the firing will be continuous; it is evident that by releasing the trigger during firing, all the parts resume their original position; the piston remains in engagement with the sear 4 and firing is stopped. The safety lever being set for single-short firing (Fig. 3), the shaft 18 presents its solid portion to the incline 14; it follows that if the trigger is pulled, the sear-lever 9 causes, by means of its hook 15, the sear 4 to swing and its head 5 to disappear; but during the disappearance of this head, the incline 14 of the lever slides upon the shaft of the safety lever in such a manner that when the piston is released, the tail 8 of the sear is also released; the head 5 of the sear can rise as soon as the piston has moved sufficiently far forwards, and once the shot has been fired, can sink and then rise in order again to retain the piston; but it is necessary to release the trigger in order to enable the hook 15 of the sear-lever 9 to engage in front of the arm 8 of the sear and to actuate it afresh.

Finally, the safety-lever 18, 19 being placed in the position shown in Fig. 4, the projection 21 of the safety lever, which serves at the same time to hold the lever in the casing, depresses the sear-lever 9 so as to avoid its hook 15 being engaged by the arm 8 of the sear 4.

The cocking movement will be possible, but any action upon the trigger will only have the effect, if this trigger is not completely wedged by the abutment of the hook 15 upon the casing (Fig. 4), to move the hook 15 still further away from the sear 4.

The invention has been shown and described as applied to a gas-operated gun but it is evidently applicable to any other type of fire-arm.

I claim:

1. A firing mechanism for automatic fire arms comprising a pivoted trigger having a cut away portion between the trigger and

its pivot, a pin in said cut away portion spaced from the trigger pivot, a sear-lever having a curved end fitting against said trigger pivot and about said pin, said sear-lever extending forwardly of the gun from the trigger and having an upstanding plug from its intermediate part with an inclined rear face and an upstanding hook at its forward free end, a sear pivoted at its intermediate part above said hook and extending forwardly of its pivot point with a tail piece extending rearwardly of the pivot, a coil spring connecting the rear end of said tail piece with a sear-lever adjoining said pin, said sear having an arm extending downwardly from the pivot thereof into close proximity to said hook and having a slotted lower end for guiding the free end of said sear-lever, and a rotary safety device mounted in conjunction with the inclined surface of said lug having three graduated steps for shifting the sear-lever and hook into or out of engagement with said arm of the sear or into an intermediate position adapted to engage and release the sear upon each movement of the trigger.

2. A firing mechanism for automatic fire arms comprising a pivoted trigger, a sear-lever extending forwardly from the trigger and pivoted thereto, said sear-lever having an inclined lug at its intermediate part and an upstanding hook at its free end, a sear pivoted above said hook and having an arm extending down for engagement with the hook, said arm having a slotted lower end in which the free end of said sear-lever is guided, a tail piece on said sear, a coil spring connected between said tail piece and the sear-lever near the pivoted end thereof, and a safety device mounted for cooperation with said inclined lug and having three stepped surfaces for engagement with said inclined lug whereby to move said sear-lever to engage or entirely disengage said hook from the arm of the sear or to move said sear-lever to an intermediate position where the hook will engage or slide off the arm of the sear at each pulling of the trigger.

3. A firing mechanism for automatic fire arms comprising a sear having a pivot point and a tail piece extending substantially horizontally to the rear of said pivot point, an arm extending down from said sear, a sear-lever extending below and substantially parallel with said sear and tail piece and having a hook at its forward free end adapted to engage with said arm of the sear, a pivoted trigger, means whereby said sear-lever is pivotally connected to said trigger and for movement with a trigger, resilient means between said sear-lever and said tail piece of the sear, a safety device acting on said sear-lever for shifting the hook into or out of engagement with said

arm or to an intermediate position for engagement and slipping off the arm at each movement of the trigger.

4. A firing mechanism for automatic fire arms comprising a sear having a tail piece and an arm extending downwardly from the sear, a pivoted trigger, a sear-lever coupled for movement with said trigger and pivoted to said trigger for swinging movement of its own, said sear-lever having at its free forward end means for en-

gaging with the arm of said sear, a single resilient means directly coupling said tail piece of the sear with the rear end portion of said sear-lever, and a safety device acting on the intermediate part of said sear-lever for shifting the same into and out of engagement with said arm or to an intermediate position engaging with and slipping off said arm at each movement of said trigger. 15 20

CHARLES SUTTER.
